(57) **CLAIM**

The ornamental design for a transparent display and storage box, as shown and described.

DESCRIPTION

FIG. 1 is a perspective view of a transparent display and storage box of the present invention;

FIG. 2 is a front elevational view of the box;

FIG. 3 is an enlarged view taken on circle 3 of FIG. 2;

FIG. 4 is a cross-sectional view taken on line 4—4 in FIG. 3;

FIG. 5 is an enlarged view taken on circle 5 of FIG. 2;

FIG. 6 is a cross-sectional view taken on line 6—6 of FIG. 5;

FIG. 7 is a left side elevational view of the box, the right side elevational view being a mirror image thereof;

FIG. 8 is an enlarged view taken on circle 8 of FIG. 7;

FIG. 9 is a cross-sectional view taken on line 9—9 of FIG. 8;

FIG. 10 is an enlarged view taken on circle 10 of FIG. 7;

FIG. 11 is a cross-sectional view taken on line 11—11 of FIG. 10;

FIG. 12 is a top plan view of the box;

FIG. 13 is an enlarged view taken on circle 13 of FIG. 12;

FIG. 14 is a cross-sectional view taken on line 14—14 of FIG. 13;
